(57) **CLAIM**

The ornamental design for a light fixture, as shown and described.

DESCRIPTION

FIG. 1 is a perspective view of a light fixture showing my new design.

FIG. 2 is a front view thereof, the rear view, right side view, and left side view being the same thereof.

FIG. 3 is a top view thereof.

FIG. 4 is a bottom view thereof.

FIG. 5 is a front view of an alternative embodiment, the rear view, right side view, and left side view being the same thereof.

FIG. 6 is a top view thereof.

FIG. 7 is a bottom view thereof.

FIG. 8 is a front view of another alternative embodiment, the rear view, right side view, and left side view being the same thereof.

FIG. 9 is a top view thereof; and,

FIG. 10 is a bottom view thereof.

The broken line showing of environmental structure is for illustrative purposes only and form no part of the claimed design.
